MAGAZINE LEAD-PENCIL.

1,124,786.

Specification of Letters Patent.

Patented Jan. 12, 1915.

Application filed January 26, 1914. Serial No. 814,285.

To all whom it may concern:

Be it known that I, JOSEPH MURCHEY, a citizen of the United States, residing at Wyandotte, in the county of Wayne and State of Michigan, have invented certain new and useful Improvements in Magazine Lead-Pencils, of which the following is a specification.

This invention relates to magazine lead pencils in which a plurality of marking points are stored in a magazine, the points being disposed in longitudinal alinement with each other; and the invention has for one of its objects the provision of the improved mechanism whereby the marking points in the magazine may be successively projected into position for use, the projecting action resulting also in ejecting the worn or broken point.

The invention has, furthermore, for its object the provision of a point-projecting member, the point-engaging end of which will be positively guided into contact with the rear or stub end of the point tube projected, and which member will also serve for holding or backing the projecting point against retrograde movement into the magazine.

Further objects of the invention will hereinafter appear and be particularly defined in the claims.

The invention has been clearly illustrated in the accompanying drawings in which similar characters denote similar parts and in which:—

Figure 1 is a longitudinal section of a magazine lead pencil embodying my invention, the projecting member being in position to project a new point forward and at the same time eject the marking point which has thus far been in use. Fig. 2 is a similar section illustrating the point-projecting member at the limit of its point-projecting movement in which position the pencil is generally used. Fig. 3 illustrates the point-projecting member together with the sleeve for operating the same, and Fig. 4 is a side view of the magazine taken at right angles to that shown in Fig. 1.

Referring to the drawings, 10 denotes a tube which serves as a magazine for a series of successively disposed marking points, the front end of said tube being preferably slitted, as at 11, to form a pair of spring jaws

whereby the cylindrical butt end of each marking point is held in position, as will be readily understood. If desired, the rear end of said magazine tube 10 may be closed by a plug 12, clearly shown in Figs. 1 and 2, it being understood that the several marking points may gravitate within the tube 10 substantially into the position shown in Fig. 1, that is to say: that the marking point p' will rest with its pointed end against the rear or butt end of the front point p .

The tube 10 is cut near its front portion to form a tongue 13 which is bent outwardly into the position shown in Figs. 1 and 2 to serve as a means for engaging and drawing inwardly the push end 14' of a projecting member or pusher 14 which extends longitudinally of the magazine and consists preferably of a strip of spring steel having at its rear end a projection 14" which may be either secured thereto or may be formed by doubling the steel strip upon itself in the manner shown in Fig. 1. This projection 14" is disposed within an aperture 15' of a sleeve 15 which constitutes the hand-operated portion or member of the pusher 14 and is mounted for free longitudinal movement relatively to the magazine 10 and also relatively to a general inclosing shell 16 which constitutes the holder of the pencil. If desired, the rear end of the magazine may be provided with a collar 17 which is cut away at 17' to form a guide-way for the pusher 14 at that end, while at its forward end said pusher may be guided in a slot 18 formed in a sleeve or surrounding tube 19 of the magazine. A filler tube 20 may be employed for centering the magazine tube 10 within the pencil shell 16, it being understood that the thickness of the inner shell 19 is such that the pusher 14 may have free sliding movement between the magazine 10 and the tube 20.

The pusher 14 is limited in its movement in both directions, by being provided with an offset portion 21 playing between the rear end of the tongue 13 and the front end of the tube 20, the distance of movement being such that when the pusher 14 has arrived in the position shown in Fig. 2, further movement in that direction will be checked by the offset 21 coming into engagement with the end of the tongue 13, as clearly shown in that figure. Here it will

also be noted that the tongue 13 has been instrumental in deflecting the end 14' of the pusher inwardly so that now this end rests against the butt end of the newly projected point p' near the central position thereof. It is therefore evident that considerable friction is established between the bent portion of the pusher and the tongue 13, so that if the pusher is left in the position shown, it will serve as a backing to prevent the marking point p' from being accidentally pushed back in the magazine.

Again referring to Fig. 1 it will be noted that the offset 21 is in engagement with one edge of the sleeve or tube 20 which is secured to the magazine 10 and therefore serves as a stop for the rearward movement of the pusher 14. At this time it will also be noted that the pusher point 14' is entirely clear of the inside of the magazine 10, so that the marking points $p-p'$ are at liberty to gravitate toward the front end. If at any time it should be desired to withdraw the projecting marking point p' of Fig. 2, it will first become necessary to retract the pusher into the position shown in Fig. 1, whereupon the marking point p' may be pushed back into the magazine by hand.

In brief, the present invention comprises a magazine pencil the salient features of which consist of the magazine proper having at one end thereof means for positively bringing the point-projecting member into engagement with the next succeeding marking point within the magazine, the bend formed in the pusher being such as to establish considerable friction between the magazine tongue and the pusher so that the latter may then serve as a backing member for the point in actual use.

Changes may be made in the particular construction of the pusher and especially in the offset portion 21 thereof, as well as in the means whereby the movement of this offset portion is limited to certain predetermined positions in conformity with the length of the marking points used in the magazine, without departing from the spirit of the invention.

I claim:

1. A lead pencil comprising a magazine adapted to receive a series of individual marking points gravitative therein, and having near its discharge end an outwardly bent tongue, and a pusher movable longitudinally of said magazine and having its front end constantly in sliding engagement with the underside of said tongue to guide the pusher into contact with the rear end of one of the marking points in the magazine.

2. A lead pencil comprising a magazine adapted to receive a series of individual marking points gravitative therein, and having near its discharge end an outwardly

bent tongue, and a pusher movable longitudinally of said magazine and having its resilient front end in sliding engagement with the underside of said tongue to guide the pusher into contact with the rear end of one of the marking points in the magazine, and means for guiding said pusher on the outer face of said magazine.

3. A lead pencil comprising a magazine adapted to receive a series of individual marking points gravitative therein, and having near its discharge end an outwardly bent tongue, a pusher movable longitudinally of said magazine and having its front end in sliding engagement with the underside of said tongue to guide the pusher into contact with the rear end of one of the marking points in the magazine, and grooved collars exteriorly on the magazine for guiding said pusher on the magazine.

4. A lead pencil comprising a magazine adapted to receive a series of individual marking points gravitative therein, and having near its discharge end an outwardly bent tongue, a pusher movable longitudinally of said magazine and having its front end constantly in sliding engagement with the underside of said tongue to guide the pusher into contact with the rear end of one of the marking points in the magazine, and means for limiting the movement of said pusher in opposite directions.

5. A lead pencil comprising a magazine adapted to receive a series of individual marking points gravitative therein, and having near its discharge end an outwardly bent tongue, a pusher movable longitudinally of said magazine and having its front end constantly in sliding engagement with the underside of said tongue to guide the pusher into contact with the rear end of one of the marking points in the magazine, said pusher having a radial projection adapted to engage the end of said tongue to limit its ejecting movement, and a stationary member on the magazine for limiting the movement of said pusher in the opposite direction to clear the path of the marking points.

6. A lead pencil comprising a magazine adapted to receive a series of individual marking points gravitative therein, and having near its discharge end an outwardly bent tongue, a pusher movable longitudinally of said magazine and having its front end constantly in sliding engagement with the underside of said tongue to guide the pusher into contact with the rear end of one of the marking points in the magazine, said magazine having at its rear end a collar provided in a groove to receive and guide the rear end of said pusher.

7. A lead pencil comprising a magazine adapted to receive a series of individual marking points gravitative therein, and having near its discharge end an outwardly

bent tongue, a pusher movable longitudinally of said magazine and having its front end in sliding engagement with the underside of said tongue to guide the pusher into contact with the rear end of one of the marking points in the magazine, grooved collars exteriorly on the magazine for guiding said pusher on the magazine, and tu-

bular members surrounding said collars to maintain said pusher within said grooves. 10

In testimony whereof I affix my signature in presence of two witnesses.

JOSEPH MURCHEY.

Correction in Letters Patent No. 1,124,786.

It is hereby certified that Letters Patent No. 1,124,786, granted January 12, 1915, upon the application of Joseph Murchey, of Wyandotte, Michigan, for an improvement in "Magazine Lead-Pencils," were erroneously issued to Harry L. Frost and Sidney S. Lenz as assignees of the entire interest in said invention, whereas said Letters Patent should have been issued to the *inventor, said Murchey and Harry L. Frost and Sidney S. Lenz*, said Frost and Lenz being assignees of *a part interest* only, as shown by the records of assignments in this office; and that the said Letters Patent should be read with this correction therein that the same may conform to the record of the case in the Patent Office.

Signed and sealed this 16th day of March, A. D., 1915.

[SEAL.]

J. T. NEWTON,
Acting Commissioner of Patents.
